DESIGN FOR A PETRI DISH OR SIMILAR ARTICLE

Harold Leon Fruitman, San Francisco, Calif.

Application June 29, 1938, Serial No. 78,137

Term of patent 14 years

To all whom it may concern:

Be it known that I, Harold Leon Fruitman, a citizen of the United States of America and a resident of the city and county of San Francisco, State of California, have invented a new, original, and ornamental Design for a Petri Dish or Similar Article, of which the following is a specification, reference being had to the accompanying drawing, forming a part thereof, and in which

Figure 1 is a top perspective view of a petri dish or similar article, showing my new design;

I claim:

The ornamental design for a petri dish or similar article, substantially as shown.

HAROLD LEON FRUITMAN.
